United States Patent Office

Des. 189,405
Patented Dec. 6, 1960

189,405

DISPLAY BOX

Milton Strumpf, 295 Scranton Ave., Lynbrook, N.Y., and Milton Schulman, 23 Park Circle, Cedarhurst, N.Y.

Filed July 15, 1959, Ser. No. 56,791

Term of patent 14 years

(Cl. D58—12)

Fig. 1 is a top plan view of a display box, showing my new design;

Fig. 2 is a front elevational view, thereof;

Fig. 3 is a side elevational view, thereof;

Fig. 4 is a vertical sectional view taken on the line 4—4 of Fig. 1;

Fig. 5 is a vertical sectional view taken on the line 5—5 of Fig. 1;

Fig. 6 is a top plan view of the box shown without the cover portion; and

Fig. 7 is a vertical sectional view taken on the line 7—7 of Fig. 6.

I claim:

The ornamental design for a display box, substantially as shown.
